Fig. 3.

Fig. 4.

A technical line drawing of a device assembly. It features a central vertical cylindrical component labeled '15' at the top. To the left, a circular base is labeled '60' at the bottom, with a vertical slot labeled '57' on its left side. A horizontal rod labeled '14' extends from the base. To the right, a vertical structure labeled '73' is shown, with a horizontal slot labeled '51' on its right side. A horizontal rod labeled '10' extends from the structure '73'. The base '60' has a circular cutout at the bottom left. The drawing is annotated with various numbers: 15, 11, 78, 77, 57, 14, 60, 73, 10, 51, and 78.

UNITED STATES PATENT OFFICE.

NATHAN J. GOLDFARB, OF BROOKLYN, AND BERNARD SACKS, OF NEW YORK, N. Y.

CLOTH-CUTTER.

1,342,210.

Specification of Letters Patent.

Patented June 1, 1920.

Application filed November 7, 1919. Serial No. 336,508.

To all whom it may concern:

Be it known that we, NATHAN J. GOLDFARB, a citizen of the United States, and a resident of the borough of Brooklyn, county 5 of Kings, city and State of New York, and BERNARD SACKS, a citizen of the United States, and a resident of the borough of the Bronx, county of the Bronx, city and State of New York, have invented certain new and 10 useful Improvements in Cloth-Cutters, of which the following is a specification.

The present invention relates to improvements in cloth cutters, and particularly such cutters having a rotary cutting blade adapted to rotate in a vertical plane and cut through a stack of cloth. An object of the invention is to provide in connection with the cutting blade, a pivoted foot embracing the blade and over which the cloth moves 15 as it is cut, and means for swinging the foot upwardly at the end of the cut, raising the stack of cloth therewith so that the lowermost layer of cloth will be cut to the same extent as the upper layers, and which would 20 not be the case if the cloth remained flat, as the end of the cut would have the curvature of the circular cutting blade.

Other objects are to provide improved operating means for lifting the foot, which 30 may be conveniently operated by the hand guiding the cutter, and means coöperating therewith to lift the guard normally protecting the edge of the cutting blade, so as to make room for the cloth as it is lifted. 35 A further object is to provide slot means in the foot embracing the cutting blade which will normally provide a support for the cloth close to and in front of the cutting edge, but which will at the same time permit 40 the foot to be raised without interference with the blade, and we further propose to provide such means which may be adjusted relatively to the cutting edge so that as the cutting edge is worn away by sharpening 45 and wear, proper relation between it and the foot may be maintained.

With these and other objects in view, embodiments of our invention are shown in the accompanying drawings, and these embodiments will be hereinafter more fully described with reference thereto, and the invention will be finally pointed out in the claims.

In the accompanying drawings, 55 Figure 1 is a front elevation of a cloth

cutter according to one embodiment of our invention;

Fig. 2 is a horizontal sectional view along the line 2—2 of Fig. 1;

Fig. 3 is a horizontal sectional view along 60 the line 3—3 of Fig. 1;

Fig. 4 is a side elevation partly in section and with parts broken away;

Fig. 5 is a transverse vertical sectional view through the line 5—5 of Fig. 1; 65

Fig. 6 is a transverse vertical sectional view through the base, with parts broken away and taken along the line 6—6 of Fig. 1;

Fig. 7 is a view similar to Fig. 3 and with 70 parts broken away, of a modified form of construction;

Fig. 8 is a front elevation of a further modified form of construction, with parts broken away; 75

Fig. 8^a is a detail view partly in section of certain portions of the form shown in Fig. 8; and

Fig. 9 shows a modified form of foot and base. 80

Similar reference characters indicate corresponding parts throughout the several figures of the drawings.

Referring to the drawings, the base 10 is provided with an upright support 11 having 85 rotatably mounted thereon at 12, the circular cutting blade 13 adapted to rotate in a vertical plane, the cutting edge of the blade extending at its lower portion into a slot 14 in the base, the upright support 11 being 90 provided with a circumferential flange 15 extending over the edge of the blade at one side, while at its other side it is spaced from the edge as at 16. A beveled gear 17 is provided at the rear side of the cutting blade 95 and is engaged by a pinion 18 provided on the end of a vertical shaft 19 journaled in an enlargement 20 of the support, the shaft being connected to and rotated by the armature 21 of a motor 22 mounted upon a circular flat portion 23 at the upper end of the enlarged portion 20 of the support 11. A horizontally disposed handle 24 is connected to the support to guide the movement of the cutter. 100

The base is hollow at its under side and is beveled at its side and ends so as to guide it readily beneath the cloth.

At the under side of the portion 23, there are provided a pair of spaced lugs 25 and 110

26 upon which is hingedly supported a plate 27, a shaft 28 extending through upstanding ears 29 and 30 on the plate and through the lugs 25 and 26, a coil spring 28^a being disposed on the shaft and normally holding the plate in its lowered position. An arcuate guard member 31 having a deflector end 32 and a flange 33 extending over the upper part of the forward portion of the cutting 10 edge is secured to the plate 27 by means of a bolt and nut 34, and circumferentially adjustable through a slot 35.

A pair of rotary beveled grinders 36 and 37 are mounted upon a bracket 38 pivotally supported on a lug 39 of the support 11 and provided with a downwardly extending crank arm 40 pivotally connected at one end of a link 41, said link being pivotally connected at its other end to a swivel pin 42 20 provided in the angle of an elbow lever 43 pivotally mounted upon a post 44 depending from the portion 23 so that by swinging the lever inwardly, the grinders will be lowered into engagement with the cutting blade. A 25 spring 43^a extending between the lever 43, and a pin 43^b on the support 20, normally holds the grinders in raised position.

Upon the plate 27 below the shaft 28 and extending rearwardly, there is provided an 30 arm 45 provided at its end with a pin 46 slidably engaging the slot 47 of a link 48 pivotally connected at one end to a swivel pin 49 provided in the lever 43 and adapted as the lever is swung inwardly, to simultaneously lift the plate 27 and the guard so that the cutting edge of the blade will be free to be engaged by the grinders.

A foot member 51 has its butt portion 52 disposed in a cut-out 53 of the base and 40 engaged by a transverse pin 54, to form a hinge about which the foot may be swung upwardly. The foot is beveled at its ends as at 55 and 56, the beveled portion 55 being of rounded contour and extending to the 45 surface of the base, the hinge portion in front of the portion 55 being flush with the base, so that the cloth will ride freely from the base along the foot member. The foot member may be longer so that it will 50 not rise at as acute an angle as illustrated. The foot is provided with a slot 57 embracing the cutting blade. In the lowered position of the foot, the slot extends for some distance in front of the cutting edge 55 and into the space there extends a filler piece 58 extending upwardly from the under side of the base through a slot 59, the base 60 of the filler piece being disposed in a groove 61 and supported at its under side by a plate 62 secured to the base 10 by means of screws 62^a. The portion of the filler piece extending above the base plate 10 is provided with a flanged portion 53 extending beyond the slot at one side and engaging the upper 65 face of the base. At the side of the plate

62, the filler piece is enlarged and provided with a threaded aperture 64 engaged by an elongated screw 65 rotatably mounted in bearing lugs 66 and provided at its outer end with a grooved head 67 disposed in a 70 cut-out 68 in the base and adapted to be engaged by a screw driver, the screw being held against longitudinal movement by means of a collar 69. By turning the screw, the filler piece will be moved toward or 75 away from the edge of the cutting blade so as to regulate the distance between the said piece and the cutting edge, the filler piece constituting in the lowered position of the foot plate, a base for the slot 57. 80

At the under side of the base, there is slidably mounted in guides 70 and 71, a rod 72, and connected at one end by a link 73 to the under side of the foot plate, the link being disposed in a slot 74 of the base plate. 85 At its other end, the rod 72 is connected by a knuckle joint 75 with a laterally swinging arm 76 provided at the lower end of a vertically disposed shaft 77, the said shaft being journaled in a passage 78 provided therefor in the support 11, and bent outwardly at its upper end as at 79 and rearwardly into a handle portion 80. By swinging the handle, the rod 72 will be shifted forwardly through the turning movement of 95 the arm 76 thereby lifting the foot plate as shown in dotted lines in Fig. 1. A spring 76^a extending between the arm 76, and a pin 76^b at the under side of the base plate 10 normally retains the foot plate in lowered 100 position. The slot 57 of the foot plate extending considerably in front of the cutting edge of the blade, it will not interfere with the said edge during the raising action, while the filler piece provides a support for 105 the cloth close to and in front of the cutting edge so that a clean cut will result.

In order to raise the guard at the same time that the foot plate is lifted, without lowering the grinder, a finger 81 is provided on the shaft 77 above the cutting blade, and engages the inner side of the plate 27 and which when the shaft 77 is rotated, will force said plate and the guard carried thereby upwardly so that the end 115 of the guard will not interfere with the cloth as it is raised by the foot plate.

The slotted connection of the link 48 of the lever 43 with the plate 27, permits of independent raising movement of the said 120 plate by operation of either the grinders or the foot plate.

In Fig. 7, we have illustrated a modified form of construction in which the handle 80 for operating the foot plate is connected to 125 the handle 43 for operating the grinders by means of a lever 82 pivotally supported upon the handle 24 and engaging pins 83 and 84 on the respective handles 80 and 43, the end of the lever engaging the pin 84 130

being bent as at 85 so as to press inwardly upon the handle 43. The movement of the handle 80 is such that it will not operate the handle 43 sufficiently to engage the grinders with the cutting blade, but will raise the guard out of the way of the cloth as it is raised by the foot plate. The handle 43 may be operated without operating the handle 80.

10 In Fig. 8, we have shown a modified form of mechanism for raising the foot plate, the rod 72 being connected at its end to a crank lever 86 pivotally mounted on the support 11 at 87 and connected at its short 15 arm to one end of a vertically movable rod 88 connected at its other end to the end of a handle lever 89 pivotally mounted at 90 on the handle 24 to swing in a vertical plane. By pressing the handle lever 89, the rod 72 20 will be moved inwardly and the foot plate raised. A spring 91 extending between the crank lever 86 and the pin 92 on the base plate, normally holds the foot plate in lowered position. The rod 88 is connected to 25 the guard plate 27 by means of a link 93 so that as the rod 88 is raised, the guard plate will also be raised.

In Fig. 9 we have illustrated a modified form of foot plate 94 provided at its under 30 side with a lug 95 movable in a slot 96 of the base plate 10 and engaged by an elongated screw 97 mounted in bearing lugs 98 and 99, being provided at its outer end with a grooved head 100 disposed in a cut-out 101 in the base 10, and adapted to be engaged by 35 a screw driver, and fixed against longitudinal movement by means of a collar 102. By turning the screw, the slot 103 of the base plate may be adjusted as desired toward or 40 away from the cutting edge.

With our improvements, a cloth cutter is provided in which the end of the cut in the cloth may be made of equal extent throughout its depth and in which the support of 45 the cloth close to the blade may be accurately regulated so as to always cause the blade to make a clean cut. The device is of simple construction and may be operated with facility.

50 We have illustrated and described preferred and satisfactory embodiments of our invention, but it is obvious that changes may be made therein within the spirit and scope thereof, as defined in the appended claims.

55 We claim:

1. In a cloth cutter, a rotary cutting blade adapted to rotate in a vertical plane, a guard extending over the edge of said blade, a longitudinal hinge for said guard, said guard 60 adapted to be raised and lowered, a horizontally disposed foot plate provided with a slot embracing said blade at its lower portion and over which the material to be cut is adapted to be moved, the end of said 65 guard being disposed in spaced relation to

said foot plate, means adapted to swing said foot upwardly into an inclined position, and means co-operatively connecting said last named means with said guard and adapted to raise said guard simultaneously with the 70 raising of said foot plate to maintain a substantially constant spaced relation between said foot plate and said guard to permit the free passing of the material therebetween.

2. In a cloth cutter, a rotary cutting blade 75 adapted to rotate in a vertical plane, a guard extending over the edge of said blade and adapted to be raised and lowered, grinder means adapted to be moved into and out of engagement with said blade to sharpen it, 80 means for moving said grinder means, means co-operatively connecting said last named means and said guard and adapted to lift said guard simultaneously with the movement into blade engaging position of said 85 grinder means, a horizontally disposed foot plate provided with a slot embracing said blade at its lower portion and over which the material to be cut is adapted to be moved, means adapted to swing said foot member 90 upwardly into an inclined position, and means co-operatively associating said last named means with said guard and adapted to raise said guard simultaneously with the raising of said foot plate. 95

3. In a cloth cutter, a rotary cutting blade adapted to rotate in a vertical plane, a guard extending over the edge of said blade and adapted to be raised and lowered, grinder means adapted to be moved into and 100 out of engagement with said blade to sharpen it, means for moving said grinder means, means co-operatively connecting said last named means and said guard and adapted to lift said guard simultaneously with the movement into blade engaging position of said 105 grinder means, a horizontally disposed foot plate provided with a slot embracing said blade at its lower portion and over which the material to be cut is adapted 110 to be moved, means adapted to swing said foot member upwardly into an inclined position, and means co-operatively associating said last named means with said guard and adapted to raise said guard simultaneously with the raising of said foot plate. 115

4. In a cloth cutter, a base plate, a rotary cutting blade supported above said base plate and adapted to rotate in a vertical plane, a horizontally disposed foot plate provided at one end with a slot embracing 120 said blade at its lower portion and over which the material to be cut is adapted to be moved, said foot plate being provided at its other end with a fixed pivot in said base plate, a link member connected to the 125 130

- base of said foot plate, a horizontally slide-
able rod connected to said link member, and
means connected to said rod adapted to be
actuated by the operator to cause sliding
movement of said rod and thereby raise and
lower said foot plate, said link member
adapted to support said foot plate in raised
position.
5. In a cloth cutter, a base plate, a rotary
10 cutting blade adapted to rotate in a vertical
plane, a horizontally disposed foot plate
provided with a slot embracing said blade
at its lower portion and over which the ma-
terial to be cut is adapted to be moved, a
15 rotatable shaft journaled upon said base
plate fixed against longitudinal movement
and having a screw threaded portion, means
associated with said base plate provided
with a threaded passage engaged by said
20 threaded portion of said shaft, said means
adapted to be moved by the turning of said
screw and adapted to regulate the distance
between the base of the slot and the cutting
edge of said blade.
- 25 6. In a cloth cutter, a rotary circular
cutting blade adapted to rotate in a ver-
tical plane, a horizontally disposed foot
plate provided with a slot embracing said
blade at its lower portion and over which
30 the material to be cut is adapted to be moved,
said slot extending substantially in front of
the cutting edge of said blade, a filler mem-
ber disposed in the opening of said slot in
front of said cutting blade, said filler mem-
35 ber forming a base for said slot relatively
close to said cutting blade, and means
adapted to adjust said filler member toward
or away from the cutting edge of said
blade.
- 40 7. In a cloth cutter, a base plate, a cutting
blade adapted to rotate in a vertical plane,
a horizontally disposed foot plate pivotally
mounted on said base plate and provided
with a slot embracing said blade at its lower
45 portion and over which the material to be
cut is adapted to be moved, said slot ex-
tending substantially in front of the cutting
edge of said blade, a filler member mounted
on said base plate and disposed in the open-

ing of said slot in front of said cutting 50
blade, means adapted to adjust said filler
member toward and away from the cutting
edge of said blade, said filler member form-
ing a base for said slot, relatively close to
55 said cutting blade, and means adapted to
swing said foot plate upwardly into in-
clined position away from said filler mem-
ber, said slot being free from contact with
said cutting blade in said raised position.

8. In a cloth cutter, a base plate, a cir- 60
cular cutting blade adapted to rotate in a
vertical plane, a horizontally disposed foot
plate pivotally mounted on said base plate
and provided with a slot embracing said
blade at its lower portion and over which 65
the material to be cut is adapted to be
moved, said slot extending substantially in
front of the cutting edge of said blade, a
filler member mounted on said base plate
and disposed in the opening of said slot in 70
front of said cutting blade, said filler mem-
ber forming a base for said slot relatively
close to said cutting blade, and means adapt-
ed to swing said foot plate upwardly into
75 inclined position away from said filler mem-
ber, said slot being free from contact with
said cutting blade in said raised position.

9. In a cloth cutter, a circular cutting
blade adapted to rotate in a vertical plane,
a horizontally disposed foot plate having 80
a fixed pivot on said base plate and provided
with a slot embracing said blade at its lower
portion and over which the material to be
cut is adapted to be moved, said slot extend-
ing substantially in front of the cutting 85
edge of said blade, in the lowered position
of said foot plate, and means adapted to
swing said foot plate upwardly into in-
clined position, said slot being relatively
close to said cutting edge, and free from 90
contact therewith in the raised position of
said foot.

In testimony that we claim the foregoing
as our invention, we have signed our names
hereunder.

NATHAN J. GOLDFARB.
BERNARD SACKS.
